GENERAL'S ROOM.

No. 6,139

Sept. 10- 1872.

UNITED STATES PATENT OFFICE.

GEORGE C. WRIGHT, OF NEW YORK, N. Y., ASSIGNOR TO E. S. HIGGINS & CO., OF SAME PLACE.

DESIGN FOR CARPET.

Specification forming part of Design No. 6,139, dated September 10, 1872.

Specification describing a Design for Carpets, invented by GEO. C. WRIGHT, of New York, county of New York and State of New York.

The nature of my design is fully represented in the accompanying photographic illustration, to which reference is made.

A represents a square panel, ornamented with scroll-work J and figures M and N, the latter in the form of a Maltese cross. C is a band surrounding panel A, and composed of a scroll and dot. At b the band assumes an inward curve, the outline substantially as at C. E is a circular figure conforming to the band at b, upon which rests the figure K, in the form of a lyre, inside of which is a palm-leaf; B, a panel surrounded with band D; c c, a chevron completing band D; I I, six-sided figures resting between panels A and B. I I

are ornamented with elongated set figures. F, a star-shaped figure in center of circular frame E; L, scroll-work partially covering ground of panel B; G and H, set figures.

I lay no claim to the forming a pattern of panels surrounded with bands and set figures. The distinctive character of my design is found in the construction of bands surrounding panels, in combination with the scroll-work and figures inwrought into the panels.

What I claim as my invention is—

A design for carpets in which the panels and bands are combined, substantially in the manner above described.

GEO. C. WRIGHT.
